Primary Examiner—James R. Largen

[57] **CLAIM**

The ornamental design for a watering can, as shown and described.

DESCRIPTION

FIG. 1 is an isometric view of a watering can showing my new design;

FIG. 2 is a side elevational view thereof, the opposite side being a mirror image of the side shown;

FIG. 3 is a top plan view thereof;

FIG. 4 is a bottom view thereof;

FIG. 5 is a cross sectional view taken on line 5—5 of FIG. 2; and

FIG. 6 is an isometric view of a modified form of the watering can shown in FIG. 1.

F/G. 3

FIG. 4

FIG. 5

FIG. 6
